ELECTROLYTIC ALKALI CHLORINE CELL

John A. Flynn and John W. Ingersol, Tacoma,
Wash., assignors to Hooker Electrochemical
Company, Niagara Falls, N. Y., a corporation
of New York

Application September 11, 1940, Serial No. 356,338

6 Claims. (Cl. 204—257)

More particularly our invention relates to an alkali chlorine cell for production of caustic alkali, chlorine and hydrogen from alkali metal chlorides.

Our invention is a modification of the alkali chlorine cell disclosed in Patent No. 1,866,065. One object of our invention is to provide a cell having certain of the characteristics of the cell disclosed in this patent, but adapted to replace cells of the elongated type in cell houses already constructed and provided with foundation piers spaced for cells of that type. Another object of our invention is to provide a cell of the general type referred to but having no concrete in its construction.

Referring to the drawings:

Fig. 1 is a side elevation of our cell, in section along the line *a—a* of Fig. 2, to show its interior construction.

Fig. 2 is a plan view of our cell, in section along line *b—b* of Fig. 1.

Fig. 3 is an end elevation of our cell to a larger scale, in section along the line *c—c* of Fig. 2.

Figs. 4, 5 and 6 are perspective views showing details of construction of the cathodic electrode members.

Fig. 7 is an enlarged plan view showing further details of construction of said members.

Referring to the figures:

The cell comprises an anode assembly, a cathode assembly resting upon it and a cover resting upon the cathode assembly.

The anode assembly comprises a built up elongated rectangular steel structure consisting of large I beam 1, laid flat on its side, angles 2 and filler strips 3, which make up the bottom and side walls of a trough-shaped base member, the ends of which are closed by plates 4 and 5 and insulating blocks 6, which are retained in position by straps 7. Blocks 6 serve not only to insulate the cathode assembly from the anode assembly but also to carry its weight.

The uppermost flanges and web of I beam 1 form between them a channel within which the anodic electrodes, consisting of graphite blades 8, are mounted. Anode blades 8 are thin, flat-faced elongated plates. They are placed with their longer edges, and hence their flat faces, vertical. In the embodiment illustrated, they are arranged in pairs, edge to edge, each pair extending transversely of the channel formed by I beam 1. Between adjacent pairs of anode blades extend the hollow foraminous cathodic electrodes to be described in detail later. The lower ends of the anode blades are embedded for a short distance in slab 9, of low melting metal or alloy, such as solder or lead, preferably the latter, which serves not only to hold the anode blades in position, but also to conduct electric current to them from steel I beam 1. Lead slab 9

fills the entire space between the uppermost flanges of I beam 1 nearly to the upper edges of the flanges. It is formed by pouring the molten lead into the channel and allowing it to flow around the ends of the anode blades. Each anode blade has the holes drilled through it below the level to which the blade is to be immersed in the molten lead. Each blade is also notched where it is contiguous with the adjoining blade, to provide clearance between the ends of contiguous blades. The lead flowing through these holes and clearances anchors the blades in the lead slab securely.

In order to protect the steel and lead of the anode assembly against electrolysis, their upper surfaces are coated with a layer of bitumen 11. This is likewise poured in while molten and flows through the clearances between contiguous blades. In Fig. 3 the plane of the section is behind the left hand anode and in front of the right hand blade so that the bitumen is in section on one side only.

The cathode assembly comprises an elongated rectangular main frame 12, formed of two long and two short members, of channel section, welded at the corners. The shape and proportions of frame 12 conform to those of the anode assembly base member and the lower flange of frame 12 is adapted to rest at the ends of the frame upon insulating blocks 6 and bitumen layer 11.

The active surface of the cathode assembly consists of a series of flattened, tubular, foraminous cathodic electrodes 13, preferably of steel wire screen, extending transversely of frame 12, placed with their flat sides vertical and alternating with anode blades 8. The thickness of these cathodic electrodes 13 is somewhat less than the space between the faces of adjacent anode blades, so that clearance is left for circulation of the electrolyte. The height of these cathodic electrodes is the same as that of frame 12. The upper and lower edges of these electrodes are rounded; that is to say, the flat side walls are joined by fillets, preferably semicircular, at top and bottom, thus avoiding sharp angles. The length of anode blades 8 is such that their upper ends extend to about the same height as the upper edges of cathodic electrodes 13. Between the lower edges of these cathodic electrodes and layer 11 clearance is likewise provided for circulation of electrolyte.

Cathodic electrodes 13 not only lie between anode blades 8 but preferably also enclose their outer vertical edges, as will clearly appear at 14, Fig. 2. The construction of the cathodic electrodes will be more readily understood by reference to Figs. 4, 5 and 6, which illustrate one method of forming these electrodes. As thus constructed each electrode is made up of two sheets of wire screen 15. Each sheet is first

wrapped around a form having the dimensions of the active upper portion of a pair of contiguous anode blades, as they are set up in the anode assembly, plus the clearance desired for circulation of electrolyte at the flat faces and edges. The two ends of the sheet are butted and welded together along seam 16, forming a flattened "cylinder" (in the mathematical sense, in which a cylinder is any surface generated by a straight line moving parallel to itself). The upper and lower edges of the "cylinder" are then peened outward, preferably over a 90 degree circular fillet, until they form flanges at top and bottom of the "cylinder." Two of these sheets are then butted and welded together along seam 17. When the desired number of cathodic electrodes 13 have been formed in this way (depending upon the current under which the cell is designed to operate and other practical considerations), scallops are cut out of four strips of wire screen, of which short sections are illustrated at 18 (Figs. 4, 5 and 6). The radii and pitch of these scallops are the same as those of the rounded ends of the flanges of cathodic electrodes 13. The scallops of strips 18 are then welded to the corresponding rounded ends of the cathodic electrode flanges, as illustrated by the dotted lines in Fig. 7. The completed assembly of cathodic electrodes 13 and strips 18 is then placed inside frame 12 and the straight outer edges of the strips 18 butted against and welded to frame 12 along the sharp edges which the upper and lower surfaces of the flanges make with the inner surface of the web of the channel section. As cathodic electrodes 13 are of the same height as the channel of which frame 12 is formed, strips 18 are flush with the top and bottom surfaces of the flanges of frame 12. Finally, rods 19 are pushed transversely through holes in the web of frame 12 and the hollow interior of the cathodic electrodes 13 and welded to frame 12 at their ends. These rods are of a diameter slightly less than the clear interior width of members 13, so that they slide through freely, but are nevertheless adapted to support the side walls of electrodes 13 against collapse under hydrostatic pressure. The clearance between the rounded ends or roots of electrodes 13 and the inner faces of the web of the channel forming frame 12 provides a space into which the liquid and gaseous products of electrolysis are received. This space forms a passage extending along each side of the cell and across the ends, through which passage the liquid and gaseous products of electrolysis are conducted to their respective exits, to be indicated later.

The top or cover of the cell comprises an elongated rectangular steel main frame 20, formed by two long and two short members, of angle section, welded at the corners. The shape and outer dimensions of frame 20 conform to those of frame 12 and the horizontal leg of the angle is adapted to rest upon the upper flange of the latter frame. Between the upper legs of the angles forming the long sides of frame 20 is sprung an arch of wire screen 21, welded along its edges to the frame. The ends of this arch are likewise closed by wire screen 22, welded to the screen of the arch at the edges. Screen 21 and 22 is coated on both sides and through the mesh with bitumen 23, or equivalent chlorine-resistant, non-conducting, preferably thermo-plastic material, the coating of bitumen extending down inside the vertical legs of the angles comprising frame 20 and beneath their horizontal legs. Bitumen coating 23 is pro-

tected on the outside by a covering 24 of fibrous material, which may be asbestos fiber and cement.

At a number of points e. g., four, spaced longitudinally of the cell, straps 25, terminating in lugs 26, are provided. The base number of the anode assembly is likewise provided with lugs 27, extending beyond angle 2 and positioned to conform with lugs 26. By means of lugs 26 and 27 and bolts 28 the three parts of the cell, namely 10 the anode assembly, cathode assembly and cover, may be securely bolted together so as to form liquid tight joints between them.

The wire screen of the cathodic electrodes is coated with a permeable diaphragm, as indicated by the speckled surfaces, dividing the cell into anode and cathode compartments. This is preferably of asbestos fiber, and may be applied in accordance with the process disclosed in U. S. Patent Nos. 1,855,497 and 1,865,152.

The fiber coating 24 of the cell cover serves to insulate the cell against radiation of heat through its top surface. This insulation may be augmented by a coating of similar material 29 within the flanges of the channels forming frame 12.

Current is conducted to and from the cell by means of bus bars 30 and 31, connected to the cathode and anode assemblies respectively.

Electrolyte is supplied to the cell through orifice 32. The liquid product is withdrawn through pipe 33. The chlorine escapes at 34 and hydrogen at 35.

While we have illustrated and described one type of construction of our cell, we do not wish to be strictly limited thereto. Any equivalent construction would come within the scope of our invention. In particular, other methods of forming the cathodic electrodes 13 will suggest themselves to persons skilled in the art. Broadly speaking, we claim any construction in which flattened, tubular, foraminous, diaphragm-covered cathodic electrodes, alternating with flat sided anodic electrodes, extend between side walls in which openings are formed through which liquids percolating through the diaphragm, as well as liquid and gaseous products of electrolytic decomposition and chemical reaction, can be drawn off.

We claim as our invention:

1. In an electrolytic alkali chlorine cell, a cathode assembly comprising a flat, normally level, rectangular, liquid-retaining, metal plate frame structure, having end and side members adapted to carry the cell current, and housing an inner, foraminous, caustic alkali-resistant metal structure comprising a plurality of tubular, parallel, spaced, horizontally aligned, cathodic electrodes, each comprising a top wall, a bottom wall and two flat side walls and having its ends conductively fixed each to the inner surface of one of the side walls of said frame structure, adjacent cathodic electrodes being separated by clear spaces open at top and bottom and adapted to alternate and co-operate with upright, flat-sided, chlorine-resistant anodic electrodes projecting upwardly from below, said foraminous structure being adapted to be covered on its anode facing surfaces with permeable, chlorine-resistant diaphragm material, and means for withdrawing gaseous and liquid products of electrolysis from the interior of said cathodic electrodes.
2. In an electrolytic alkali chlorine cell, a cathode assembly comprising a flat, normally level, rectangular, liquid-retaining, metal plate frame structure, having end and side members adapted

to carry the cell current, and housing an inner, foraminous, caustic alkali-resistant metal structure comprising a plurality of tubular, parallel, spaced, horizontally aligned, cathodic electrodes extending perpendicularly with respect to said side walls, each comprising a top wall, a bottom wall and two flat side walls and having its ends conductively fixed each to the inner surface of one of the side walls of said frame structure, adjacent cathodic electrodes being separated by clear spaces open at top and bottom and adapted to alternate and co-operate with upright, flat-sided, chlorine-resistant anodic electrodes projecting upwardly from below, said foraminous structure being adapted to be covered on its anode facing surfaces with permeable, chlorine-resistant diaphragm material, and means for withdrawing gaseous and liquid products of electrolysis from the interior of said cathodic electrodes.

3. In an electrolytic alkali chlorine cell, a cathode assembly comprising a flat, normally level, rectangular, liquid-retaining, metal plate frame structure, having end and side members adapted to carry the cell current, and housing an inner, foraminous, caustic alkali-resistant metal structure comprising inner end walls paralleling the end walls of said plate structure and conductively affixed thereto at top and bottom and a plurality of tubular, parallel, spaced, horizontally aligned, cathodic electrodes, adjacent cathodic electrodes being separated by clear spaces open at top and bottom and adapted to alternate and co-operate with upright, flat-sided, chlorine-resistant anodic electrodes projecting upwardly from below, said foraminous structure being adapted to be covered on its anode facing surfaces with permeable, chlorine-resistant diaphragm material, each of said cathodic electrodes comprising a top wall, a bottom wall and two flat side walls, leaving both ends open, the spaces between the side walls of adjacent cathodic electrodes being bridged at the ends, forming discontinuous inner walls along the side walls of said plate structure, with corridors between into which the cathodic electrodes may freely deliver products of electrolysis, the spaces between outer side walls of outer cathodic electrodes and said inner end walls being likewise bridged at their ends, the outer edges of said top and bottom walls and upper and lower edges of the bridge walls being conductively joined through fitted filler strips to the inner surface of the side walls of said frame structure; and means for withdrawing products of electrolysis from within said corridors.

4. In an electrolytic alkali chlorine cell, a cathode assembly comprising a flat, normally level, rectangular, liquid-retaining, metal plate frame structure having end and side members adapted to carry the cell current and housing an inner, foraminous, caustic alkali-resistant metal structure comprising a plurality of flattened foraminous metal cylinders outwardly flanged at their ends, the length of the flanged cylinders being substantially equal to the height of said frame, said cylinders being aligned with their axes vertical and joined by the edges of the flanges along their adjacent flat sides, the free edges of the resulting unitary structure being conductively joined to the walls of said frame structure by fitted filler strips, said resulting unitary structure constituting a plurality of thin, parallel, spaced, aligned, tubular, foraminous cathodic electrodes open at both ends and

spaced, aligned, tubular, foraminous cathodic electrodes open at both ends and separated by clear spaces open at top and bottom and adapted to alternate and co-operate with flat-sided, chlorine-resistant anodic electrodes projecting upwardly from below, said foraminous structure being adapted to be covered on its anode facing surfaces with permeable, chlorine-resistant diaphragm material, and means for withdrawing gaseous and liquid products of electrolysis from the interior of said cathodic electrodes.

5. In an electrolytic alkali chlorine cell, a cathode assembly comprising a flat, normally level, rectangular, liquid-retaining, metal plate frame structure having end and side members adapted to carry the cell current and housing an inner, foraminous, caustic alkali-resistant metal structure comprising a plurality of flattened foraminous metal cylinders outwardly flanged at their ends, the length of said cylinders being substantially equal to the height of said frame, said cylinders being aligned with their axes vertical and having the edges of the flanges along their adjacent flat sides butted and joined, the free edges of the resulting unitary structure being conductively joined to the walls of said frame structure by fitted filler strips, said resulting unitary structure constituting a plurality of thin, parallel, spaced, aligned, tubular, foraminous cathodic electrodes open at both ends and separated by clear spaces open at top and bottom and adapted to alternate and co-operate with flat-sided, chlorine-resistant anodic electrodes projecting upwardly from below, said foraminous structure being adapted to be covered on its anode facing surfaces with permeable, chlorine-resistant diaphragm material, and means for withdrawing gaseous and liquid products of electrolysis from the interior of said cathodic electrodes.

6. In an electrolytic alkali chlorine cell, a cathode assembly comprising a flat, normally level, rectangular, liquid-retaining, metal plate frame structure having end and side members adapted to carry the cell current and housing an inner, foraminous, caustic alkali-resistant metal structure comprising a plurality of flattened foraminous metal cylinders each having two long flat and two short rounded sides and outwardly flanged at their ends, the length of said cylinders being substantially equal to the height of said frame, said cylinders being aligned with their axes vertical and joined by the edges of the flanges along their adjacent flat sides, the scalloped edges of the resulting unitary structure formed by the flanges of said short rounded sides being conductively joined to the walls of said frame structure by fitted filler strips, said resulting unitary structure constituting a plurality of thin, parallel, spaced, aligned, tubular, foraminous cathodic electrodes open at both ends and separated by clear spaces open at top and bottom and adapted to alternate and co-operate with flat-sided, chlorine-resistant anodic electrodes projecting upwardly from below, said foraminous structure being adapted to be covered on its anode facing surfaces with permeable, chlorine-resistant diaphragm material, and means for withdrawing gaseous and liquid products of electrolysis from the interior of said cathodic electrodes.
